UNITED STATES PATENT OFFICE

112,287

DESIGN FOR A CASE FOR RADIO RECEIVING OR TRANSMITTING APPARATUS

Sol J. Levy, New York, N. Y., assignor to Morris Cohn, Long Island City, N. Y., as receiver of Police Radio Corporation, a corporation of New York

Application March 2, 1938, Serial No. 75,530

Term of patent 7 years

To all whom it may concern:

Be it known that I, Sol J. Levy, a citizen of the United States, residing at New York, in the county and State of New York, have invented a new, original, and ornamental Design for a Case for Radio Receiving or Transmitting Apparatus, of which the following is a specification, reference being had to the accompanying drawing, forming part thereof, in which—

Fig. 1 is a view in front elevation of a case for radio receiving or transmitting apparatus showing my new design;

Fig. 2 is a view in end elevation of the case shown in Fig. 1;

Fig. 3 is a top plan view of the case shown in Fig. 1.

The rear portion of the case is concave from top to bottom and the bottom is substantially flat.

I claim:

The ornamental design for a case for radio receiving or transmitting apparatus, substantially as shown and described.

SOL J. LEVY.
